Charles Perley

UNITED STATES PATENT OFFICE.

CHARLES PERLEY, OF NEW YORK, N. Y.

IMPROVEMENT IN CLOSING DOORS.

Specification forming part of Letters Patent No. 37,770, dated February 24, 1863

To all whom it may concern:

Be it known that I, CHARLES PERLEY, of the city and State of New York, have invented, made, and applied to use a certain new and useful Improvement in Means for Closing Doors; and I do hereby declare that the following is a full, clear, and exact description of the nature of said invention, reference being had to the annexed drawings, making part of this specification, wherein—

Figure 1 is a side view of the upper part of a door with the casing in section, and Fig. 2 is a plan of the apparatus as applied upon the top of the door.

Similar marks of reference denote the same parts.

In the outer doors of banks, houses, public buildings, schools, &c., doors are often required that will open either outward or inward, and the same must not come against a rigid bearing, or else the glass often introduced in such doors is broken. Neither must the door be without a stopping-point, or the wind partially opens the same.

The nature of my said invention consists in an arrangement of pulleys on the door-casing, combined with a saddle-piece on the door, from which a cord, or its equivalent, extends through said pulleys to a weight, in such a manner that the door can swing in either direction, and the said saddle-piece forms a stop that will prevent the wind blowing the door open, but not act suddenly or with a concussion likely to injure the door or any glass contained in the same.

In the drawings, *a* represents the door-casings, of any usual or suitable character, and *b* is the door.

c is a V-shaped style, and the edge of the door contiguous thereto is formed in a corresponding manner, so that ordinary butt-hinges, *d d*, can be used to hang the door, and the same can be opened either way.

e e' are pulleys attached to the lintel at any desired distance from the hinged edge of the door, so that the weight will have the necessary leverage upon said door in closing.

f is a pulley, over which a cord, *g*, from the weight *h* passes, and the end of said cord attaches to the saddle-piece *i* that is on the top edge of the door. This saddle-piece is provided with a slot taking the pin *1*, and the end next the pulleys *e e'* is curved to correspond with them, the cord being attached at the apex.

The operation is as follows: The parts being at rest, as in Fig. 2, the saddle-piece *i* is drawn between the two pulleys *e e'* by the cord *g* and weight *h*, and there held sufficiently to prevent the door vibrating with a gust of wind. When the door is swung either way, the saddle-piece turns by the action of the pin *1* in the slot, with one of the rollers *e* or *e'* as the center, and then the pin *1*, by its farther movement, draws the saddle away from the pulleys and elevates the weight *h*. When the door is released, the weight draws the door shut, the cord running over the pulley *e* or *e'* and *f*, and the saddle, coming to place either immediately or after a slight vibration from the momentum of the door, holds said door steady.

The face of the saddle may take against the metal flange carrying the rollers *e e'*, instead of against the rollers themselves, to avoid wear or concussion on them, and said face of the saddle-piece may be lined with leather or other material to prevent noise. Springs might be substituted for the weight *h*.

Having thus described my said invention, what I claim, and desire to secure by Letters Patent, is—

Saddle-piece *i*, receiving the weight-cord, in combination with the rollers *e e'*, and acting to close the door in the manner and as specified.

In witness whereof I have hereunto set my signature this 15th day of April, 1861.

CHARLES PERLEY.
